UNITED STATES PATENT OFFICE

165,955

COMBINATION TELEVISION, RADIO-PHONO-
GRAPH, AND BEVERAGE CABINET

Samuel E. Adler, Chicago, Ill., assignor to Admiral Corporation, Chicago, Ill., a corporation of Delaware

Application April 20, 1951, Serial No. 14,903

Term of patent 14 years

(Cl. D56—4)

To all whom it may concern:

Be it known that I, Samuel E. Adler, a citizen of the United States, residing at Chicago, in the county of Cook, State of Illinois, have invented a new, original and ornamental Design for a Combination Television, Radio-Phonograph, and Beverage Cabinet, of which the following is a specification, reference being had to the accompanying drawings, forming part thereof.

Fig. 1 is a front elevational view of a combination television, radio-phonograph, and beverage cabinet, showing my new design, the doors of which are closed;

Fig. 2 is a top plan view thereof;

Fig. 3 is a front elevational view of the cabinet, the doors being shown in open position;

Fig. 4 is also a top plan view, the doors being shown in open position;

Fig. 5 is a sectional view, the planar origin of which is represented by the line 5—5 of Fig. 1;

Fig. 6 is a fragmentary sectional view, the planar origin of which is represented by line 6—6 of Fig. 5; and

Fig. 7 is a fragmentary sectional view, the

planar origin of which is represented by line 7—7 of Fig. 5.

The dominant features of my design reside in that portion shown by full lines of the drawings.

I claim:

The ornamental design for a combination television, radio-phonograph, and beverage cabinet, as shown and described.

SAMUEL E. ADLER.
